UNITED STATES PATENT OFFICE

WILSON B. WIGLE, OF COMPTON, CALIFORNIA

CONTROL HEAD FOR OIL AND GAS WELLS

Application filed January 11, 1930. Serial No. 420,121.

This invention relates generally to oil well equipment, more specifically to casing control heads, and is an improvement over my co-pending application filed December 24, 5 1928, bearing Serial No. 328,154.

The main object of this invention is to provide a casing control head for oil wells constructed in such a manner that space between two strings of casing may be packed off in the control head on the first string without any fittings projecting above the last or upper coupling on the second string while drilling a hole for the next string of casing or tubing.

Another object of this invention is to provide a casing head for oil wells constructed in such a manner that the oil string or tubing may be packed off at any required point and held against downward movement by 20 slips placed in the control head.

A further object of this invention is to provide a casing head for oil wells in which a fluid tight seal may be made between two strings of casing in a control head while 25 drilling for the next string of casing without any danger of the packing being dislodged or blown out of the control head due to gas pressure developed in the casing below the packing.

A still further object of this invention is to provide a casing head construction in which two strings of casing may be packed off and the hole for the next string drilled without the necessity of applying a control 35 head for said next string of casing until it has been landed.

Other objects and advantages will be apparent from the following description, reference being had to the accompanying drawings, in which:

Fig. 1 is a vertical section taken through a plurality of well casings and tubing showing the improved casing control head in 45 connection therewith;

Fig. 2 is a horizontal section taken on line 2-2 of Fig. 1;

Fig. 3 is a vertical section similar to Fig. 1 showing a modified form in which casing slips are employed to support the casing during 50 cementing operation.

Referring more specifically to the drawings, particularly to Fig. 1, 10 designates the first string of casing or water string which has been landed and cemented in the usual 55 manner in a well hole. The control head generally designated at 12 consists of a member 14 secured to the upper end of the casing by screw threaded connections 15 and is provided with outlets 16 from which extend the usual vent pipes 17 controlled by valves not shown. The member 14 is provided with a seat 20 adapted to receive a bushing 22 upon which is mounted a packing ring 24 formed of resilient material, and 60 a metallic ring 28.

The above packing rings and bushing are formed in segments (see Fig. 2) in order that they may be placed in the member 14 around the second string of casing or tubing 28, the 70 bushing and packing rings being placed in the control head when the tubing is in a position to be landed in an oil zone, or cemented in as the case may be.

When the tubing serves as an oil string its 75 uppermost coupling 30 engages the upper metallic ring 26, the weight of the tubing compressing the resilient packing ring 24. If it is necessary to cement the tubing 28 the coupling 30 is lowered to a point below the 80 control head, the tubing is then stretched sufficiently after the cement has set to bring the coupling to a position so that its bottom face will rest on the packing when released, the section of tubing extending above the coupling 30 is then removed.

After the tubing 28 has been landed as above described, a collar 32 is applied to the member 14 by a screw threaded connection 34 and serves to hold the packing rings in place 85 90

in the member 14 against upward displacement due to any excessive gas pressure developed between the casing 10 and tubing 28, the collar having a shoulder 35 engaging 5 the upper ring 26.

Should it be desired to bring the well in after the second string 28 has been landed, a "Christmas tree" coupling (not shown) may be secured to the upper end of the collar 32 10 which is internally threaded as indicated at 36 to receive such fitting or a second control head member designated at 38 if the second string 28 is cemented in above the oil sands.

During drilling of the hole for the last 15 string 40 the second control head need not be connected, as the first and second are then packed off, it being particularly noted that the upper end of the coupling 30 projects above the upper end of the collar 32, thereby 20 protecting it against damage particularly to the internal threads therein by the tools employed while drilling the hole for the third or last string 40.

After the hole for the last string has been 25 completed a pair of packing rings 42 formed of resilient material are placed in the bore 44 formed in the collar 32, the packing ring encircling the lower end of the coupling 30 and resting on the upper ring 26. The second 30 control head member 38 is then screwed into the fitting, the action of which compresses the packing rings 42 and forms a fluid tight joint by engagement between the upper face 45 of the coupling 30 and a shoulder 46 formed 35 on the interior of the member 44.

A split bushing 48 is placed in the upper end of the control head member 38 upon which is mounted a split packing ring 45 formed of resilient material engaged by a 40 split metallic ring 46 which in turn is engaged by the upper coupling 47 of the string 40, it being understood that the above packing need not be positioned in the member 44 until the last string is ready to be landed.

45 The length of the tubing projecting above the coupling is removed and the third control head 50 is secured to the member 44 by screw threaded joint 51 also compressing packing rings 52 placed in the bore 53 formed therein 50 and resting on the upper ring 46, the second control head is provided with the usual flow or outlet pipes 54.

The upper control head 50 is provided with 55 threaded openings 56 from which extend the flow pipes 57, and is also provided with male and female threads 58 and 60 respectively to which the usual "Christmas tree" (not shown) may be connected.

Under certain conditions it is necessary to 60 land and cement a string of casing or tubing at a point between the couplings. This is accomplished by the construction shown in Fig. 3, and consists of a control head member 62 screw threadedly connected to the first 65 string of casing 63, and is provided with out-

let pipes 64 extending from threaded openings entering a bore 65 terminating in a tapered bore 66 adapted to receive a plurality of slips 67.

After the second string of casing 68 has 70 been lowered to the required depth in the well hole for cementing it in, the slips 67 are placed in the bore 66 at which time their teeth engage the wall of the second string and thereby prevent downward movement of it.

The length of tubing projecting above the control head is then cut off a short distance 75 above the slips and a coupling 70 secured thereto preferably by welding, the underside of which engages a split ring 71 adapted to expand a resilient packing ring 72 resting on the upper face of the slips, it being understood that the casing is stretched prior to placing the packing and rings on the slips, the packing being expanded on release of the 80 casing, it being also understood that the slips do not immediately engage or grab the casing 85 when released, thereby permitting expansion of the packing ring.

Upward displacement of the packing rings 90 due to gas pressure developed between the strings of casing is prevented by a fitting 74 having a shoulder 75 engaging the ring 71 and connected to the member 62 by screw threads 76.

The third or last string of tubing 78 extends through a control head generally designated at 80 which consists of a member 81 adapted to expand rubber packing rings 82 positioned in the fitting 74. Slips 84 are 100 mounted in the tapered bore 85 of the member 81 and serve to hold the tubing 78 against downward movement until it may be cemented in and packed off.

I claim:

1. A casing head for wells comprising a body member adapted to be connected to a string of well casing landed in a well, said member having a seat formed in its upper end, a metal bushing in said seat, a resilient packing ring mounted on said bushing, a tubing string having a coupling, a metal ring disposed on said packing ring for engaging said coupling and receiving the weight of said tubing string, a collar having a shoulder formed thereon engaging the metal ring and connected to said body member for compressing the resilient packing ring to form a fluid tight seal between said casing and said tubing string when landed in the well, and a second body member screw threaded into said collar to form a fluid tight joint between said coupling on the tubing string and said collar.

2. A casing head for oil wells comprising a body member adapted to be connected to a string of well casing, said member having an internal seat formed in its upper end, a split metal bushing in said seat, a resilient packing ring mounted upon said bushing, a tubing string, a coupling secured to said tubing, a 120

metal ring disposed on said packing ring adapted to be engaged by the shoulder of said coupling when said tubing string is landed in the well, the weight of the tubing string compressing said packing ring to form a seal between the casing and tubing strings, and a collar threadedly connected to said control head for applying additional pressure to said resilient packing ring, a second body member 5 screw threaded into said collar, a plurality of resilient packing rings in said collar resting on said metal ring therein, said second body member compressing the resilient packing rings in said collar and at the same time 10 forming a fluid tight seal between the coupling on the tubing string and said collar.

In testimony whereof I affix my signature.
WILSON B. WIGLE.
